(57) **CLAIM**

The ornamental design for an anti-collision part of a mop holder for a cleaning robot as shown and described.

DESCRIPTION

Anti-collision part of a mop holder for a cleaning robot
1.1 is a front view of an anti-collision part of mop holder for cleaning robot, showing our new design;

1.2 is a back view thereof;

1.3 is a left view thereof;

1.4 is a right view thereof;

1.5 is a top view thereof;

1.6 is a bottom view thereof;

1.7 is a front perspective view thereof; and

1.8 is a rear perspective view thereof.

The broken lines in the reproductions depict the portions of the mop holder that form no part of the claimed design.

1 Claim, 6 Drawing Sheets
